UNITED STATES PATENT OFFICE.

CLIFFORD E. IVES, OF CHICAGO, ILLINOIS, ASSIGNOR OF ONE-THIRD TO ANDREW C. PREBLE AND TWO-THIRDS TO IVES & STERN, A VOLUNTARY ASSOCIATION, BOTH OF CHICAGO, ILLINOIS.

AUTOMATIC LOCK FOR ELEVATOR DOORS.

Application filed March 13, 1926. Serial No. 94,574.

My invention relates to automatic locks for elevator doors and has to do more particularly with such locks as are adapted for holding the sliding doors closed except when the elevator is at the landing, and at which time the lock is operated by the elevator to permit opening the doors, which last act renders the elevator inoperative until the doors are again closed.

An object of my invention is to produce an automatic lock of the above character which is sturdy in construction, positive in operation, comparatively cheap to manufacture, and simple and of few parts.

For a better understanding of my invention reference is to be had to the accompanying drawing, in which—

Fig. 1 is a face view of the lock applied adjacent the elevator door and shown along the line 1—1 of Fig. 3, with the parts in normal or locking condition;

Fig. 2 is a cross sectional view along the line 2—2 of Fig. 1;

Fig. 3 is a vertical cross sectional view along the line 3—3 of Fig. 1 with the parts in normal or locking condition;

Fig. 4 is a vertical sectional view along the line 4—4 of Fig. 1 with the elevator operated lever actuated to release the locking arm, so as to permit opening the door;

Fig. 5 is a diagrammatic view illustrating one form of application of the lock to a double door;

Fig. 6 shows a section of the lock supporting rail cut away for the locking bolt; and

Fig. 7 is a diagrammatic view of an elevator control circuit with the lock contacts interposed therein.

Referring now more in detail to the construction employed, I have shown the lock applied adjacent a vertically slidable door A which door is mounted by its side angle iron 10 between the wall slide, which consists of the inner and outer rails 11—12 separated by the interposed strip 13 so as to form a guideway 14 in which the one flange of the angle iron 10 rides.

In the upper sliding door construction, upper and lower doors A and B are provided which slide in the guideways as stated, being connected by a chain 15 running over a pulley 16 and having its opposite ends connected to the doors A and B so that as one section of the door is operated the other

one will likewise move. This chain 15 is thus positioned so that an intermediate space 17 is provided, and it is this space that my lock is adapted to fit.

Referring now more in detail to the lock construction, it comprises a suitable housing C which is a self-contained unit and adapted to be applied to the outer side of the rail 12 by screws 18, said rail 12 being cut away as indicated at 19 in Fig. 6 to permit the locking bolt to pass through into the path of the door.

The locking bolt D is preferably in the form of a pivotally mounted bar supported upon a shaft 20 extending through the walls of the casing C, the bolt D being freely rotatable upon the shaft which is fixed. This bolt is very effective because of its peculiar shape and disposition, the upper laterally extending arm 21 normally passing through the slide rail 12 into the path of the door angle 10 to lock it against opening. The locking bolt D extends downwardly, carrying a stud 22 at its lower end which stud serves several different purposes. For one thing, it is engaged by one arm of spring 23 which normally presses against the stud 22 so as to hold the locking extension 21 in the path of the door. This stud 22 also cooperates with a locking bar E, which bar is slidably supported by shafts 20 and 25 by having the portions 26—27 positioned between said shafts 20—25 and the wall 28 of the casing. This locking bar E has a locking slot 29 through which the locking pin 22 extends, the bar E being shown in its normal or locking position in Fig. 3 with the shoulder 30 of the slot engaging the pin 22 so as to prevent movement of the locking bolt D. Before this bolt may be moved and thereby permit opening of the doors, the locking bar E must be actuated to free the pin 22 carried by bolt D. In order to move the locking bar E so as to unlock the bolt, I provide an elevator actuated arm F which is adjustably mounted upon a rotatably supported shaft 25, so that the arm may be adjusted to properly meet the actuating cam 32 carried by the elevator. This arm F has a roller 33 at its upper end which is engaged by the cam 32 in the ascent and descent of the elevator, and the lock with roller 33 and the cam 32 are so positioned that when the elevator is at rest at each floor in alignment

100
105

with the floor, the cam 32 is holding the arm F in an actuated position to unlock the device. The shaft 25, as previously stated, is rotatably supported in the housing, arm F being pressed normally outwardly into the position indicated by the dotted lines in Fig. 3 by means of a spring 34 coiled around shaft 25 and having a looped extension engaging the stud 35 which is threaded into the shaft 25. This stud 35 extends into operative engagement with the locking bar E, so that when the arm F is moved into its alternate or unlocking position, the stud 35 moves the locking arm E into its alternate or unlocking position as indicated in Fig. 4. That is, the bar E is drawn downwardly so that the shoulder 30 is moved free of the pin 22, thereby freeing the bolt D to permit opening the door.

It will thus be seen that when the elevator comes to rest at the floor, the arm F has unlocked the bolt D. Therefore if the door A is now moved upwardly, the flange of the angle 10 engages the under face of the lateral extension 21. Because of this extension being lateral of the pivot point 20, a continued upward movement of the door is permitted, the angle 10 merely pushing the bolt extension 21 over as indicated in Fig. 4. This extension 21, which projects into the slideway 14 as indicated in Fig. 2, has a small extension toward the left to give the extension 21 its broadest face so as to more positively be in a position for engagement by the flange of the angle 10. These angles and doors sometimes fit very loosely, and for this reason it is desirable to have this extension 21 as wide as possible.

As so far explained, the device is adapted to maintain the elevator door locked except when the elevator is in a position registering with the floor.

As a measure of safety and in order to prevent actuation of the elevator while any door is open, I provide a pair of contacts 37-38 which are adapted to be interrupted whenever the lock is in a position to release the door, these contacts being adapted to be connected in any suitable part of the elevator control circuit so as to disable it and render it inoperative while any door is open. To this end I provide means for interrupting the circuit through these contacts 37-38 when the locking bolt 21 is in an unlocking position and the door open as indicated in Fig. 4. Therefore I provide a lever 39 which is pivotally supported upon the shaft 25 and has an upper forked end surrounding the stud 22 carried by the bolt D. The lower end of arm 39 carries a contact making stud 40 adapted to close circuit across the contacts 37-38 when the lock is in locking position. This lever 39 is preferably of insulating material such as bakelite, so as to insulate the contact maker

40 from the rest of the apparatus. The contacts 37-38 are of a resilient material such as laminated spring bronze and are clamped between the parts 41-42 of the supporting insulating block with a hole 43 adjacent each spring to receive the end of a conductor 44. A set screw 45 is provided for each terminal and access to this set screw is secured by removing the cover plate 46. Thus to apply the conductor, the cover plate 46 is removed and the conductor inserted through an opening 47 in the lower end of the casing and slipped up into the hole adjacent the contact spring, after which the set screw 45 is set to hold the conductor against the contact. The plate 46 may then be applied so as to complete the enclosure.

In Fig. 7 I have shown diagrammatically an elevator control circuit with the starting or control lever 50 including conductors 51-52 which extend to a solenoid 53 for opening and closing the circuit of the motor M through the contacts 54 which lead to the main 55. In this control circuit running from the controller 50 to the solenoid 53 I have included the contacts 37-38 and the circuit closer 40 from the automatic lock at each floor. It will thus be seen that when any elevator door is opened, the contacts 37-38 of its locking switch are interrupted and thus the control circuit is interrupted and the elevator rendered inoperative. In order to close the circuit again, it will be necessary to close the door.

It will thus be seen that I have provided an automatic lock having certain features of construction and operation in that it is of compact form and arranged to be positioned between the narrow confines of the connecting chain on the door; it is of a construction which positively locks the door against jimmying, such as has been possible in prior locks; also the parts are so distributed and so shaped as to give the greatest strength, such for example as in the locking bolt D where the locking side, that is the tension portion to the right of the pivotal shaft 20 is extremely heavy, while the compression side to the left of the shaft is comparatively light but sufficient to take the strain imposed thereon. Also the circuit interrupter with the operating levers are of positive and sturdy construction as compared with the objectionable yielding arm devices heretofore used. Although I have shown a specific form of lock, I contemplate constructing it in other ways than that shown, and therefore do not desire to be limited to the exact structure shown, but aim to cover all that which comes within the spirit and scope of the appended claims.

What I claim as new and desire to secure by United States Letters Patent is:—

1. An automatic lock for elevator sliding doors including a vertically disposed pivot-

ally mounted locking bolt having a lateral locking extension adapted to be placed in the path of a sliding door to positively lock the door, a vertically sliding reciprocable bar normally holding the bolt against unlocking movement, and an elevator actuated lever for moving the bar to unlock the bolt to permit movement of the bolt by opening the door when the elevator registers with the floor.

2. An automatic lock for elevator sliding doors including a vertically disposed intermediately pivotally mounted locking bolt having a lateral locking extension at its upper end adapted to be placed in the path of a sliding door to positively lock the door, a vertically sliding reciprocable bar normally engaging a lateral extension on the bolt for holding the bolt against unlocking movement, and an elevator actuated lever for moving the bar to unlock the bolt to permit movement of the bolt by opening the door when the elevator registers with the floor.

3. An automatic lock for elevator sliding doors including a vertically disposed pivotally mounted locking bolt having a lateral locking extension adapted to be placed in the path of a sliding door to positively lock the door, a vertically sliding reciprocable bar normally holding the bolt against unlocking movement, an elevator actuated lever for moving the bar to unlock the bolt to permit movement of the bolt by opening the door when the elevator registers with the floor, a circuit interrupter, and means for operating the interrupter for rendering the elevator inoperative responsive to actuation of the locking bolt when the door is opened.

4. An automatic lock for elevator sliding doors including a vertically disposed pivotally mounted locking bolt having a lateral locking extension adapted to be placed in the path of a sliding door to positively lock the door, a vertically sliding reciprocable bar normally holding the bolt against unlocking movement, and an elevator actuated lever for moving the bar to unlock the bolt to permit movement of the bolt by opening the door when the elevator registers with the floor, said elevator actuated lever being restorable when the door is again closed and the elevator moves away from the floor to restore the bar to again lock the bolt.

5. An automatic lock for elevator sliding doors including a vertically disposed intermediately pivotally mounted locking bolt having a lateral locking extension at its upper end adapted to be placed in the path of a sliding door to positively lock the door, a vertically sliding reciprocable bar normally in the path of the lower end of the locking bolt to hold it against unlocking movement by the door, and an elevator actuated lever connected with the bar to move the latter out

of the path of the locking bolt to release the latter when the elevator stops in registration with the floor.

6. An automatic lock for elevator sliding doors including a vertically disposed intermediately pivotally mounted locking bolt having a lateral locking extension at its upper end adapted to be placed in the path of a sliding door to positively lock the door, a vertically sliding reciprocable bar normally in the path of the lower end of the locking bolt to hold it against unlocking movement by the door, an elevator actuated lever connected with the bar to move the latter out of the path of the locking bolt to release the latter when the elevator stops in registration with the floor, a circuit interrupter, and an intermediately pivoted lever having one end connected with the lower end of the locking bolt and its other end connected with the circuit interrupter, whereby when the door is opened the locking bolt is moved to actuate the last said lever to operate the circuit interrupter to render the elevator inoperative while the door is open.

7. An automatic lock for elevator sliding doors including an elongated narrow rectangular casing, a locking bolt intermediately pivotally supported upon a shaft at one end of the casing and longitudinally disposed therein, a lateral extension at one end of the bolt adapted to be placed in the path of a sliding door to positively lock the latter, an elevator actuated lever mounted upon a shaft spaced apart from the bolt shaft in said casing, a bar slidably held in the casing by said two shafts, means normally interlocking the bar and bolt to prevent movement of the bolt so as to lock the door, and means responsive to operation of the elevator actuated lever for operating the bar to release the bolt and permit opening the door and the operation of the bolt thereby when the elevator registers with the floor.

8. An automatic lock for elevator sliding doors including an elongated narrow rectangular casing, a locking bolt intermediately pivotally supported upon a shaft at one end of the casing and longitudinally disposed therein, a lateral extension at one end of the bolt adapted to be placed in the path of a sliding door to positively lock the latter, an elevator actuated lever mounted upon a shaft spaced apart from the bolt shaft in said casing, a bar slidably held in the casing by said two shafts, means normally interlocking the bar and bolt to prevent movement of the bolt so as to lock the door, and means responsive to operation of the elevator actuated lever for operating the bar to release the bolt and permit opening the door and the operation of the bolt thereby when the elevator registers with the floor, said last means including a transverse stud carried

by said elevator actuated lever shaft and extending into operative engagement with the sliding bar.

9. An automatic lock for elevator sliding doors including an elongated narrow rectangular casing, a locking bolt intermediately pivotally supported upon a shaft at one end of the casing and longitudinally disposed therein, a lateral extension at one end of the bolt adapted to be placed in the path of a sliding door to positively lock the latter, an elevator actuated lever mounted upon a shaft spaced apart from the bolt shaft in said casing, a bar slidably held in the casing by said two shafts, means normally interlocking the bar and bolt to prevent movement of the bolt so as to lock the door, means

responsive to operation of the elevator actuated lever for operating the bar to release the bolt and permit opening the door and 20 the operation of the bolt thereby when the elevator registers with the floor, a circuit interrupter positioned at the other end of the casing, and a lever pivotally mounted in the casing between the locking bolt and interrupter having one end connected with the bolt and the other end with the interrupter to operate the latter and render the elevator inoperative when the door is 25 opened.

In witness whereof, I hereunto subscribe my name this 5th day of March, 1926.

CLIFFORD E. IVES.
